AWNING LOUVER

Albert Donald Mortrude, Detroit, Mich., assignor to A. Belshaw, Inc., Detroit, Mich., a corporation of Michigan

Application June 24, 1953, Serial No. 25,639

Term of patent 14 years

(Cl. D21—6)

To all whom it may concern:

Be it known that I, Albert Donald Mortrude, a citizen of the United States of America, residing in the city of Detroit, in the county of Wayne, State of Michigan, have invented a new, original, and ornamental Design for an Awning Louver, of which the following is a specification, reference being had to the accompanying drawing, forming a part thereof, wherein:

I claim:
The ornamental design for an awning louver, as shown.
